(57) **CLAIM**

The ornamental design for a bocce ball retriever, as shown and described.

DESCRIPTION

FIG. 1 is a front view showing my new design for a bocce ball retriever;

FIG. 2 is a side view of FIG. 1;

FIG. 3 is a back view of FIG. 1;

FIG. 4 is a bottom view of FIG. 1;

FIG. 5 is a bottom view showing the design in FIGS. 1–4 combined with an optional ball stabilizer; and,

FIG. 6 is a top, side and front perspective view showing the design in FIGS. 1–4 combined with an optional handle and an optional ball stabilizer.

The broken lines showing the handle and ball stabilizer in FIGS. 5 and 6 are for illustrative purposes only and form no part of the claimed design.
